FOREIGN PATENT DOCUMENTS

GB 2065456 A 7/1981

Primary Examiner — Cynthia R Underwood(74) *Attorney, Agent, or Firm* — Luedeka Neely Group, P.C.(57) **CLAIM**

The ornamental design for a curtain hook, as shown.

DESCRIPTION

FIG. 1 is a perspective view of a curtain hook of my new design;

FIG. 2 first side planar view of the curtain hook of FIG. 1;

FIG. 3 is a second side planar view of the curtain hook of FIG. 1, rotated from the view of FIG. 2;

FIG. 4 is a front planar view of the curtain hook of FIG. 1;

FIG. 5 is a rear planar view of the curtain hook of FIG. 1;

FIG. 6 is a top planar view of the curtain hook of FIG. 1; and, FIG. 7 is a bottom planar view of the curtain hook of FIG. 1.

The broken lines in the drawings are included for the purpose of illustrating unclaimed features and form no part of the claimed design.

1 Claim, 5 Drawing Sheets(56)
